INVENTOR

John DiLibero

UNITED STATES PATENT OFFICE.

JOHN DI LIBERO, OF PROVIDENCE, RHODE ISLAND.

DESIGN FOR AN EMBLEM OR ARTICLE OF SIMILAR NATURE.

Application filed October 1, 1928. Serial No. 28,333. Term of patent 14 years.

To all whom it may concern:

Be it known that I, JOHN DI LIBERO, a citizen of the United States, residing at Providence, in the county of Providence and State of Rhode Island, have invented a new, original, and ornamental Design for an Emblem or Article of Similar Nature, of which the following is a specification, reference being had to the accompanying drawing, forming part hereof.

Figure 1 is a plan view of an emblem or article of similar nature, showing my new design. Figure 2 is a cross-sectional view thereof taken on line A A.

I claim:

The ornamental design for an emblem or article of similar nature as shown.

JOHN DI LIBERO.
